Application March 28, 1933, Serial No. 663,163

15 Claims. (Cl. 149—16)

This invention relates to machines for operating upon hides, skins and pieces of leather. While the invention is illustrated as embodied in a machine for performing fleshing operations upon hides and skins, it is to be understood that the invention and various important features thereof may have other applications and uses.

Machines commonly employed in beamhouse operations upon hides and skins comprise characteristically a bladed cylinder, a bed roll for presenting the work to the cylinder, and one or more pinch or feed rolls arranged in co-operative relation with respect to the bed roll and operative with the bed roll to feed the work past the bladed cylinder. Because of the nature of the work the bed roll is arranged to press the work yieldingly against the bladed cylinder so that the bed roll, while maintaining substantially uniform pressure on the work, may adjust its position in accordance with variations in the thickness of the various portions of each piece of work as it passes between the bed roll and bladed cylinder. For the same reason, the feed rolls are arranged to press the work yieldingly against the bed roll. Since the bed roll, in its adjusting movements with respect to the bladed cylinder, moves also in directions toward and away from the feed rolls, provision should be made by which the feed rolls are enabled to maintain proper feeding pressure in spite of variations in the thickness dimensions of the work and of the described movements of the bed roll. Accordingly it is an object of this invention to provide for greater certainty and uniformity in the feeding of hides, skins, and pieces of leather in beamhouse and other similarly constructed machines, and to secure better treatment of the pieces of work due to better control thereof while they are undergoing machine operations. Other objects of the invention are to provide a machine of the beamhouse type which will be simple and durable in construction and especially efficient for the purpose intended.

To these ends, and in accordance with an important feature of the invention, there is provided in the illustrated machine a feeding means wherein a member operative to support a piece of work against the thrust of an operating tool is arranged to regulate the feeding pressure of another member or members as said first-mentioned member adjusts itself to the tool in accommodating variations in the thickness of the piece of work undergoing treatment. By this arrangement, as the work supporting member adjusts itself with respect to the tool to accommodate variations in the thickness of the work, a corresponding movement of a work feeding member, or of a plurality of such members, is effected to insure uniformity in the feeding of the work in spite of such variations in the work. Conveniently the work feeding member is mounted independently

of the work supporting member and is positively moved through connections to said work supporting member whereby the work feeding member is caused to maintain a predetermined normal spaced relation with respect to said work supporting member during movement of the latter to accommodate variations in the thickness of the work. In a preferred form of the invention the work supporting member is movable alternately to receive the work and to present it to the work treating tool in an organization wherein the work feeding member is pivotally mounted for movement toward and from the work presenting member, cam means being provided under control of the work supporting and presenting member and operative to cause the work feeding member to maintain a predetermined spaced relation with respect to the work supporting and presenting member.

In the illustrated construction, which is designed specially for operations upon large pieces of work, such as hides and skins, wherein differences in the thickness dimensions in the various portions of each piece of work are substantial in extent, two work feeding rolls are provided for co-operation with a bed roll in feeding the work past a work treating bladed cylinder, the work feeding rolls being mounted upon a carrier pivotally mounted in the frame of the machine in an arrangement wherein a cam and cam slot connection is provided between the bed roll and said carrier by which the latter is positively moved by the bed roll as the latter adjusts itself to variations in thickness of the work, whereby the two work feeding rolls supported by the carrier are caused to make corresponding adjustments with respect to said bed roll to maintain a suitable feeding pressure of a predetermined minimum value during all movements of the bed roll while it is in work presenting position with respect to said bladed cylinder.

Other features of the invention relate to a simple and compact arrangement of driving means for the work feeding members including the work supporting and presenting member whereby the said members are driven from the bladed cylinder at the desired lower rate of speed through a planetary reduction gear mechanism.

These and other important features of the invention and novel combinations of parts will now be described in detail in the specification and then pointed out more particularly in the appended claims.

In the drawings,—

Fig. 1 is a view in front elevation and partly in section of a fleshing machine illustrating one embodiment of the invention;

Fig. 2 is an end view looking from the right in Fig. 1 with parts broken away to disclose sub-

stantially all of the operating structure to the line III—III of Fig. 1;

Fig. 3 is a view along the line III—III of Fig. 1 looking in the direction of the arrows;

Fig. 4 is an end view partly in section and looking from the left in Fig. 1;

Fig. 5 is a detail view of the work engaging parts of the machine; and

Fig. 6 is a diagrammatic view illustrating various positions of the work presenting and work feeding members.

In the illustrated machine, which is designed specially for fleshing operations upon untanned hides and skins, there is provided as the operating tool a cylinder 10 having blades 12 particularly adapted to remove connective tissue, fat, and flesh scraps or bits from the flesh surfaces of hides and skins. It is to be understood, however, that a cylinder with another type of blade 20 may be substituted for the fleshing cylinder when it is desired to put-out a tanned skin or set a tanned hide or when it is desired to perform one of the other beamhouse operations upon untanned hides or skins, such as unhairing or scudding or putting-out. The cylinder 10 is mounted on a shaft 11 for rotation in bearings in the frame of the machine, the shaft 11 of the cylinder being provided with a pulley 14 which may be driven from any suitable source of power.

For presenting pieces of work, such as that shown at 15, to the bladed cylinder 10 there is provided in the illustrated construction a work support in the form of a bed roll 16, shaft 17 of which is carried in bearings provided by swing arms 18 and 20 mounted for rocking movement about a pivotal axis below the bed roll. For moving the bed roll 16 between the work receiving position of Fig. 3 and the work presenting position of Figs. 4 and 5, there is provided a shaft 22 rotatable in journals in the machine frame, the said shaft carrying a pair of eccentrics one of which is shown at 24 in Figs. 3 and 4. Surrounding each eccentric 24 is an eccentric strap 26 with which there is rigidly connected a slotted arm 28 serving as a pitman by which the eccentric is connected to the swing arm 18. Extending through an opening in a hub portion 30 of said arm 28 is a rod 32 to the free end of which is fastened a slide member 34 having oppositely disposed grooves to receive slidably the side bars of the arm 28. Interposed between the hub portion 30 of the arm 28 and the slide member 34 is a spring 36 surrounding said rod 32. At its other end the rod 32 is extended through a sleeve 38 adjustable in a bearing 40 carried by the swing arm 18, the said rod 32 being prevented from endwise movement in one direction within the sleeve 38 by its head portion 42 rigid with the end of the rod 32. It will be understood that the sleeve 38 which is screw threaded within the bearing 40 is adjustable to permit adjustment of the rod 32 with respect to the pitman 28, adjustment of the tension of the spring 36 being secured by proper manipulation of the nut 42 on the rod 32. By this arrangement of parts it is possible to adjust initially the pressure with which the bed roll 16 is caused to press the work against the bladed cylinder 10, and to vary such pressure in accordance with the demands of the work and as required by wear upon both the bed roll and the bladed cylinder. It is to be understood that the description of the parts by which motion is transmitted from the eccentric 24 to the swing arm 18 applies with equal force to the driving parts between the cor-

responding eccentric, not shown, and the swing arm 20. For connecting the two swing arms there is provided a cross bar 44 (Figs. 1 and 4).

To insure proper feeding of the work there is provided in the illustrated construction a pair of feed rolls 50 and 52 which co-operate with the bed roll 16. For convenience the roll 50 may be referred to as a feed roll while the roll 52 may be designated a pinch roll although both rolls perform substantially the same function in feeding the work. It will be readily apparent upon inspection of Figs. 4 and 5 that the bed roll 16 will yield to the right in these figures when a thicker portion of the work is fed in between said bed roll and the bladed cylinder 10. In order that the feed roll 50 and pinch roll 52 may be caused to maintain substantially the same spaced relation with respect to the bed roll 16 as the latter moves back and forth with respect to the bladed cylinder 10 to accommodate variations in the thickness of the work, the said rolls 50 and 52 are mounted upon a carrier comprising two like members 54 pivoted upon shafts 56 and 57 in alignment with each other in the upper part of the frame of the machine. Hence the carrier is mounted for rocking movement about a pivotal axis furnished by shafts 56 and 57 located above the bed roll and substantially vertically over the pivotal axis of the swing arms which support the bed roll. This mounting of the carrier 54 to rock on an axis almost directly over the bed roll constitutes part of a simple and efficient construction for securing movement of the feed rolls in properly spaced relation to the bed roll. Each pivoted carrier member 54 is provided with a swing arm 55 having a bearing 57a (Fig. 1) for a shaft 58 of the feed roll 50, the said swing arm 55 being pivoted at 59 to the carrier 54 and to a block or clevis 60 having rigidly connected thereto the lower end of a rod 62 which passes through a threaded sleeve 64 adjustable in a block 66 pivoted at 68 in an upper part of the member 54. Surrounding the rod 62 is a spring 70 which is tensioned to force the block or clevis 60 downwardly with a yielding pressure whereby the feed roll 50 may be pressed yieldingly against a piece of work on the bed roll 16. It is to be understood that the other end of the shaft 58 of the feed roll 50 is similarly supported in the other carrier member 54 for yielding movement to secure a yielding pressure on the feed roll 50 with respect to work on the bed roll at the other ends of said rolls.

Upon inspection of Fig. 4 it will be observed that the pinch roll 52 is mounted upon the carrier members 54 in substantially the same manner as the feed roll 50, a block or clevis 72 being backed by a spring 74 and being held against separation from the carrier member 54 by a rod 76 rigidly secured to said block or clevis 72. Pivoted to the block or clevis 72 at 78 is a swing arm 80 adapted rotatably to support one end of a shaft 82 upon which the feed roll 52 is mounted. It will be clear then that the support for the shaft 82 of the feed roll 52 is the carrier 54, since the rods 76, which furnish the direct support for the adjacent ends of the swing arms 80, are connected to and supported by the said carrier 54. As shown in Fig. 4, the swing arm 80 is pivoted upon a shaft 86 in the frame of the machine so that the roll 52 during its downward movement is constrained to move about the axis of the shaft 86. In other words, the shaft 86 and the swing arm connections thereto furnish a guiding

means for the feed roll 52 during movements of the latter.

Preferably, and as shown, the carrier members 54 are controlled by connections with the bed roll 16, said connections comprising an extension 90 rigid with each swing arm 18 and 20, each extension 90 carrying at its end a cam roll 92 fitted for movement along a cam slot 94 in a forwardly projecting portion 96 of each carrier member 54.

As will readily be observed upon inspection of Fig. 4, movement of the bed roll 16 and of the swing arm 18 to the right in said figure will result in rocking the carrier member 54 about the axis of its pivot 56 in a counterclockwise direction with the result that during the first part of said movement the feed roll 50 and the pinch roll 52 are caused to move with the bed roll 16 to maintain their predetermined spaced relation with respect to the bed roll 16. In other words, a suitable feeding pressure between the two rolls 50, 52 and the bed roll 16 is maintained in spite of work-adjusted movement of the bed roll 16 away from the bladed cylinder 10. Upon the described movement of the swing arm 18 to the right in Fig. 4 to accommodate a thicker portion of the work between it and the bladed cylinder 10, the carrier member 54, in moving about its pivots at 56 and 57, carries the feed roll 50 in an upward direction along an arc whose center is found in the axis of the pivot 56. At the same time the pinch roll 52, which is on the other side of the pivot 56, is moved downwardly and forwardly so as to maintain its proper spaced relation with respect to the bed roll 16. Proper movement of the pinch roll 52 is secured by the action of the carrier member 54 in co-operation with swing arms 80 pivoted upon shaft 86 in the frame of the machine.

The relationship of the two feed rolls 50, 52 with respect to the bed roll 16 at the extremes of the inner and outer movements of adjustment of the bed roll 16 with respect to the bladed cylinder 10 is shown diagrammatically in Fig. 6. Solid lines are employed to indicate the relationship of the roll 50, 52 to the bed roll 16 when the bed roll 16 is spaced at its minimum distance with respect to the cylinder 10, the relationship of the same rolls 50, 52 with respect to the bed roll 16 being shown in dash lines when the bed roll 16 is at its extreme position of adjustment away from the bladed cylinder to accommodate the thickest portions of the work for which the particular machine is adapted. This figure also shows in dot-and-dash lines the relative positions of the feed rolls 50, 52 with respect to the bed roll 16 when the latter is in open or work receiving position. From this figure it will be seen that the feed roll 50 is lifted away from the path of the bed roll 16 while the latter is moving to work receiving position so that the two rolls 50 and 16 do not contact with each other during movement of the bed roll to work receiving position nor during movement of the bed roll back toward work presenting position with respect to the bladed cylinder 10. By this latter arrangement a piece of work positioned upon the bed roll 16 while the latter is in work receiving position is not carried forcibly into contact with the feed roll 50 while the bed roll is moving to work presenting position, the arrangement being such that the feed roll 50 moves into work gripping position with respect to the work on the bed roll 16 an instant before the bed roll presents the work to the bladed cylinder 10. It will furthermore be observed that, while the pinch roll 52 follows the

bed roll during outward adjusting movement of the latter away from the bladed cylinder 10, the pinch roll 52 is retracted as the bed roll advances toward work presenting position with respect to the bladed cylinder 10, the pinch roll being operative, however, to engage the piece of work on the bed roll 16 just before the work is presented to the cylinder 10. It follows from the foregoing disclosure that the feed rolls 50, 52 maintain a predetermined normal spaced relation with respect to the bed roll 16 while the latter is in work presenting position with respect to the bladed cylinder 10 even though the bed roll varies considerably in its spacing with respect to the cylinder in accommodating variations in the thickness of the work. By this arrangement proper feeding of the work is secured at all times and particularly at the time when prior constructions are apt to fail, that is, when thick portions of the work appear between the bed roll and the bladed cylinder, causing the bed roll to move away from the bladed cylinder and also away from the feed rolls since the latter were not constructed and arranged to follow the bed roll.

Means is provided in the illustrated machine 25 for driving all of the movable parts of the machine from a single shaft, an advantage being that in motorizing the machine only one motor will be needed to furnish the necessary power. Conveniently the movable parts are driven from 30 the shaft of the bladed cylinder, this being effected through an especially compact and advantageous arrangement of gear mechanism, as will now be described. Upon reference particularly to Fig. 2, it will be seen that the shaft 11 of the 35 bladed cylinder 10 carries at its right end a pinion 100 arranged in mesh with gears 102, 104 carried by stub shafts 106, 108, respectively, said shafts being mounted in bearings provided by a circular movable plate 110 rotatable within a 40 casing 112. Fixed to the shaft 106 is a pinion 114 and to shaft 108 a similar pinion 116, pinions 114 and 116 being in mesh with a circular rack bar 118 secured to the casing 112. Since the rack bar 118 is stationary the pinions 114 and 45 116 not only rotate but travel bodily around a path concentric with respect to the circular rack. This means that the plate 110 is rotated by the travel of the pinions 114, 116. Secured to travel with the plate 110 is a pinion 120 concentric with 50 respect to the axis of the shaft 11, said pinion 120 being arranged in mesh with a large gear wheel 122 freely rotatable upon the shaft 22 when it is not clutched thereto. Arranged in mesh with the gear wheel 122 is a gear 124 secured to a shaft 55 126 to which is fastened a somewhat smaller gear 128 arranged in mesh with a gear 130 fixed upon a shaft 132 journaled at one end in a bored out portion of pivot shaft 57. It will thus be seen that shafts 126 and 56 are continuously driven 60 so long as the shaft 11 of the bladed cylinder is in rotation.

Secured to the shaft 126 (Fig. 3) is a gear 134 arranged in mesh with a gear 136 secured to the shaft 86 which also carries fixed thereto a pinion 65 140. Pinion 140 is in mesh with a pinion 142 carried by a stub shaft 144 on the swing arm 80, said pinion 142 being also in mesh with a pinion 146 on the shaft 82 which carries the pinch roll 52. Hence, pinch roll 52 is continuously rotated while 70 the bladed cylinder 10 is in rotation.

Fixed to the shaft 56 is a gear 150 in mesh with a pinion 152 secured to the stub shaft 59, the latter carrying also fixed thereto a second pinion 156 which is in mesh with a pinion 158 secured 75

to the shaft 58 of the feed roll 50. It follows that the feed roll 50 is continuously rotated while the bladed cylinder 10 is in rotation.

The bed roll 16 is stationary while it is in work receiving position so that the operator may place a piece of work thereon. Furthermore, the bed roll does not begin its rotation until just an instant before it presses the work against the bladed cylinder 10. For driving the bed roll in the manner described there is provided a long-toothed gear 160 (Fig. 4) secured to the shaft 17 of the bed roll. To mesh with the gear 160 for the purpose of driving the latter is a long-toothed gear 162 secured to the shaft 58 of the feed roll 50. Hence, as the bed roll approaches the bladed cylinder 10 the two gears 160, 162 come into mesh with each other whereby the shaft 17 of the bed roll is driven from the continuously rotating shaft 58 of the feed roll 50.

As heretofore pointed out the continuously rotating gear wheel 122 (Fig. 2) is mounted for rotation upon the shaft 22 but may be clutched to the shaft to rotate the latter. This clutching of the gear wheel 122 to the shaft 22 may be accomplished through clutch mechanism of a well-known construction such as that indicated at 170 in Fig. 2 of the drawings. Upon depressing a treadle 172 (Figs. 1 and 3), the clutch 170 is actuated to clutch the gear wheel 122 to the shaft 22 with the result that the shaft 22 is rotated, but only for one-half turn, the purpose being to move the bed roll 16 between work receiving and work presenting positions and to maintain said bed roll in one or the other position until the treadle 172 is again actuated by the operator. In the illustrated construction this is accomplished by connections from the treadle 172 which comprise a lever 174 (Fig. 1) pivoted at 176 on the frame of the machine and arranged to be operated by the treadle 172 upon downward movement of the latter. Upon downward movement of said treadle 172, a lever 178 pivoted at 180 is rocked in a counterclockwise direction, thus pulling down upon a rod 182 by which a boss member 184 is displaced with respect to a cooperating boss member 186, thus permitting the member 186 to move to the right in Fig. 1 under pressure of a spring 188 whereby the clutch 170 is thrown into operation and at the same instant a brake device 190 is released. Since the treadle 172 is released after its first depression by the operator, the boss member 184 is returned to its initial position by a spring 192 (Figs. 1 and 2) so that the boss member 186 at the end of a half revolution rides back upon the high point of the boss member 184, thus releasing the clutch and resetting the brake 190. It follows that, upon depressing the treadle 172 while the parts are in the position shown in Fig. 3, the shaft 22 is rotated together with its eccentrics 24 whereby the pitmen 28 are operated to move the bed roll 16 to work presenting position with respect to the bladed cylinder 11, the shaft 22 stopping at the end of a half revolution to hold the bed roll in its work presenting position (Fig. 4). Subsequently the operator steps upon the treadle 172 a second time whereby the shaft 22 is caused to rotate through another 180° to return the bed roll 16 to the work receiving position of Fig. 3.

In operating the machine a piece of work, such as a hide or skin 15, is placed over the bed roll 16 with about one-half of the hide or skin hanging down from the rear side of the bed roll. The operator then depresses the treadle 172 whereupon the bed roll is caused to move to work pre-

senting position with respect to the bladed cylinder 11. As the bed roll approaches the cylinder 11 the feed roll 50 moves toward the bed roll to grip the work on the bed roll just an instant before the latter presses the work against the cylinder 11. Furthermore, the pinch roll 52 is so positioned at the end of the movement of the bed roll as to press the work firmly against the bed roll so that both feed roll 50 and pinch roll 52 serve in co-operation with the bed roll 16 as work feeding means, both feed rolls and the bed roll turning in the direction to feed the work out of the machine toward the operator while the bladed cylinder 10 operates upon the work. Since the bed roll 16 is held yieldingly in its work presenting position with respect to the cylinder 10, by springs 36, it may yield away from the cylinder when thicker portions of the work appear between the bed roll and cylinder, this movement of the bed roll being accompanied by corresponding movements of the feed roll 50 and pinch roll 52 whereby full feeding pressure between the feed rolls and the bed roll is maintained. Furthermore, when thinner portions of the work appear between the bed roll and cylinder the bed roll moves closer to the cylinder followed again by the feed roll 50 and the pinch roll 52. It will be understood that the machine is adjusted to operate upon pieces of work most effectively within a certain range of thicknesses. Hence, no matter how much a given piece of work may vary in thickness within said given range the work feeding means remains highly effective, thereby contributing markedly to the good results obtained in the operation of the machine upon the pieces of work.

Having described my invention, what I claim as new and desire to secure by Letters Patent of the United States is:

1. In a machine for treating sheet material, a tool for operating on a piece of work, a member arranged to support the piece of work against the thrust of the tool, said tool having its operating surface arranged substantially parallel to the work supporting surface of the work supporting member, two work feeding members spaced from each other upon opposite sides of a plane passing vertically through the work supporting member and each arranged to co-operate with the work supporting member in feeding the work, and connections between said work feeding members and the work supporting member positively operated by said work supporting member to cause the work feeding members to maintain predetermined normal spaced relations with respect to the work supporting member as the latter moves toward or away from the tool in accommodating variations in the thickness of the work.

2. In a machine for operating upon hides, skins, leather, and other similar pieces of work, a rotary tool for operating on a piece of work, a member movable alternately to receive the piece of work and to present it to the tool, said tool having its axis of rotation arranged substantially parallel to the work supporting surface of the work supporting member, a work feeding member pivotally mounted for movement toward and from said work presenting member and arranged to cooperate with the latter in feeding the work, and cam means under control of the work presenting member to cause the feeding member to maintain a predetermined normal spaced relation with respect to the work presenting member irrespective of the thickness of the work as the latter passes between the work presenting member and the tool.

3. In a machine for operating upon hides, skins, leather, and other similar pieces of work, a rotary tool for operating on a piece of work, a member operative to support and present pieces of work to the tool, said tool having its axis of rotation arranged substantially parallel to the work supporting surface of the work supporting member, two work feeding members arranged to co-operate with the first-mentioned member in feeding pieces of work past the tool, a carrier for the work feeding members pivotally mounted independently of the work presenting member, and a cam and slot connection between the work presenting member and said carrier arranged to be positively operated by the work presenting member to cause said work feeding members to move in conjunction with the work presenting member to maintain predetermined normal spaced relations between said feed members and the work presenting member during movement of the latter to accommodate variations in the thickness of the work passing between said member and said tool.
4. In a machine for operating upon hides, skins, leather, and other similar pieces of work, a rotary tool for operating on a piece of work, a member arranged to support a piece of work against the thrust of the tool, said tool having its axis of rotation arranged substantially parallel to the work supporting surface of the work supporting member, said work supporting member being movable about a pivotal axis to accommodate variations in the thickness dimensions of the work passing between said member and said tool, a work feeding member arranged for co-operation with said work supporting member, a carrier for the work feeding member movably mounted in the frame of the machine to rock about a pivotal axis substantially vertically over the first-mentioned axis, and connections between the work supporting member and said carrier to cause the latter to move the feeding member in conjunction with the work supporting member to maintain a predetermined normal spaced relation between said members irrespective of the thickness of the work as the latter passes between the work presenting member and the tool.
5. In a machine for treating hides, skins, and pieces of leather, a bladed cylinder constructed and arranged to spread a hide or skin out in directions transverse to its direction of feed and to operate thereon, a yieldingly mounted bed roll operative to support pieces of work against the thrust of the bladed cylinder, swing arms supporting said bed roll and movable about a pivotal axis below the bed roll, two feed rolls arranged upon opposite sides of a plane passing vertically through the bed roll when the latter is in work-presenting relation to the bladed cylinder to co-operate with the bed roll in feeding pieces of work past the bladed cylinder, a carrier for the two feed rolls mounted in the frame of the machine to rock about a pivotal axis substantially over the axis of rotation of the bed roll while the latter is pressing the work against the bladed cylinder, and connections between said carrier and the bed roll arranged to be positively operated by the latter to maintain a predetermined normal spaced relation between the feed rolls and the bed roll during movements of the bed roll with respect to the bladed cylinder in accommodating variations in the thickness of the work passing between said bed roll and said cylinder.
6. In a machine for treating sheet material, a bladed cylinder constructed and arranged to spread a hide or skin out in directions transverse to its direction of feed and to operate thereon, a bed roll mounted to yield relatively to the cylinder and operative to support pieces of work against the thrust of the bladed cylinder, a feed roll arranged to co-operate with the bed roll in feeding pieces of work past the bladed cylinder, swing arms supporting said bed roll and movable about a pivotal axis below the bed roll to carry the bed roll between work-receiving and work-presenting positions relative to said cylinder, a carrier for the feed roll mounted independently of the bed roll, said carrier being mounted to rock about a pivotal axis substantially over the bed roll when the latter is in work-presenting relation to the cylinder, and connections between the bed roll and said carrier arranged to be positively operated by the bed roll to cause said feed roll to move with the bed roll to maintain a predetermined normal spaced relation between the feed roll and bed roll during movements of the latter to accommodate variations in the thickness of the work passing between said bed roll and said cylinder.
7. In a machine for treating sheet material, a bladed cylinder constructed and arranged to spread a hide or skin out in directions transverse to its direction of feed and to operate thereon, a bed roll mounted to yield relatively to the cylinder and operative to support pieces of work against the thrust of the bladed cylinder, a feed roll arranged to co-operate with the bed roll in feeding pieces of work past the bladed cylinder, a carrier for the feed roll pivotally mounted in the frame of the machine, said carrier having a cam slot, and a cam roll carried by said bed roll and movable along said cam slot to effect movement of the carrier and of the feed roll carried thereby to maintain a predetermined normal spaced relation between the feed roll and the bed roll during adjusting movements of the latter with respect to the bladed cylinder.
8. In a machine for treating sheet material, a bladed cylinder constructed and arranged to spread a hide or skin out in directions transverse to its direction of feed and to operate thereon, a bed roll movable between work receiving and work presenting positions with respect to said bladed cylinder, said bed roll being mounted to yield with respect to said cylinder, feed rolls arranged upon opposite sides of a plane passing vertically through the bed roll to co-operate with said bed roll in feeding the work past the bladed cylinder, and means positively operated by the bed roll to adjust the feed rolls to maintain the latter in a predetermined normal spaced relation with respect to the bed roll during adjusting movements of the latter with respect to the bladed cylinder in accommodating variations in thickness of the work passing between said bed roll and said cylinder.
9. In a machine for treating sheet material, a bladed cylinder constructed and arranged to spread a hide or skin out in directions transverse to its direction of feed and to operate thereon, a bed roll movable between work receiving and work presenting positions with respect to said bladed cylinder, said bed roll being mounted to yield with respect to said cylinder, a feed roll arranged to co-operate with the bed roll in feeding the work, a carrier for the feed roll pivoted in the frame of the machine, and cam means controlled by the bed roll to move said carrier and the feed roll carried thereby to maintain the feed roll in predetermined normal spaced rela-

tion to the bed roll during movements of the latter in accommodating variations in the thickness of the work passing between said bed roll and said cylinder.

- 5 10. In a machine for treating sheet material, a bladed cylinder constructed and arranged to spread a hide or skin out in directions transverse to its direction of feed and to operate thereon, a bed roll movable between work receiving and 10 work presenting positions with respect to said bladed cylinder, said bed roll being mounted to yield with respect to said cylinder, a feed roll arranged to co-operate with the bed roll in feeding the work, a carrier for the feed roll movably 15 mounted in the frame of the machine, a pinch roll arranged for co-operation with the bed roll in feeding the work, means to mount the pinch roll movably in the frame of the machine, means carried by the carrier and arranged to back the 20 pinch roll yieldingly against pressure of the work on the bed roll, and means operated by the bed roll to move the carrier to maintain predetermined normal spaced relations between the bed roll in engagement with one side of the work 25 and the feed and pinch rolls in engagement with the other side of the work whereby the feeding pressure of the two rolls with respect to the bed roll is maintained during adjusting movements of the bed roll with respect to the bladed cylinder.

- 30 11. In a machine for treating sheet material, a bladed cylinder constructed and arranged to spread a hide or skin out in directions transverse to its direction of feed and to operate thereon, a bed roll movable between work receiving and work presenting positions with respect to said bladed cylinder, said bed roll being mounted to yield with respect to said cylinder, a feed roll arranged to co-operate with the bed roll in feeding the work, a carrier for the feed roll pivotally 35 mounted in the frame of the machine, a pinch roll, connections between the pinch roll and said carrier whereby the latter may move the former, and cam means operated by the bed roll to move 40 said carrier, said carrier being arranged under the control of said cam means to move the feed roll and the pinch roll to maintain predetermined normal spaced relations between both rolls and the bed roll while the latter is moving to accommodate variations in the thickness of the work 45 passing between the bed roll and the bladed cylinder.

- 50 12. In a machine for treating sheet material, a bladed cylinder constructed and arranged to spread a hide or skin out in directions transverse to its direction of feed and to operate thereon, a bed roll movable between work receiving and work presenting positions with respect to said bladed cylinder, said bed roll being mounted to yield 55 relatively to said cylinder, a feed roll arranged to co-operate with the bed roll in feeding the work, a carrier for the feed roll movably mounted in the frame of the machine, a pinch roll arranged for co-operation with the bed roll in feeding the 60 work, means carried by the carrier yieldingly to back the pinch roll, and means operated by the bed roll to move the carrier to maintain predetermined normal spaced relations between the bed roll in engagement with one side of the work and the feed and pinch rolls in engagement with the 65 other side of the work whereby the feeding pressure of the two rolls with respect to the bed 70

roll is maintained during adjusting movements of the bed roll with respect to the bladed cylinder.

13. In a machine for treating sheet material, a bladed cylinder constructed and arranged to spread a hide or skin out in directions transverse to its direction of feed and to operate thereon, a bed roll movable between work receiving and work presenting positions with respect to said bladed cylinder, said bed roll being mounted to yield relatively to said cylinder, a feed roll arranged to cooperate with the bed roll in feeding the work, a carrier for the feed roll pivotally mounted in the frame of the machine, a pinch roll mounted to move with said carrier, and cam means operated by the bed roll to move said carrier, said carrier being arranged under the control of said cam means to move both the feed roll and the pinch roll to maintain predetermined normal spaced relations between both rolls and the bed roll while the latter is moving to accommodate variations in the thickness of the work passing between the bed roll and the bladed cylinder.

14. In a machine for operating upon hides, skins, leather, and other similar pieces of work, a rotary cylinder, power means arranged to drive said cylinder continuously, a bed roll movable between work receiving and work presenting positions with respect to said cylinder, a feed roll for co-operation with the bed roll in feeding the work past the cylinder, a shaft rotatably mounted in the frame of the machine, connections between the shaft and the bed roll arranged to move the latter alternately between work receiving and work presenting positions, a gear wheel mounted for rotation on said shaft, a driving connection between the power driven cylinder and said gear wheel to drive the latter continuously during rotation of the cylinder, a driving connection between said gear wheel and said feed roll whereby the latter is driven continuously 40 during rotation of the said cylinder, and a treadle operated clutch mechanism arranged to connect said gear wheel to said shaft to move the bed roll alternately between work receiving and work presenting positions.

45 15. In a machine for operating upon hides, skins, leather, and other similar pieces of work, a rotary cylinder, power means arranged to drive said cylinder continuously, a bed roll movable between work receiving and work presenting positions with respect to said cylinder, a feed roll for co-operation with the bed roll in feeding the work past the cylinder, a shaft rotatably mounted in the frame of the machine, connections between the shaft and the bed roll arranged to move the latter alternately between work receiving and work presenting positions, a gear wheel mounted for rotation on said shaft, a planetary reduction gear mechanism arranged to be driven by said power driven cylinder and also arranged to drive 55 said gear wheel continuously during rotation of said cylinder, a gear in mesh with said gear wheel and arranged to drive the feed roll, and a treadle operated clutch mechanism arranged to secure said gear wheel to said shaft for revolution of 60 said shaft through 180° only upon each operation of the treadle operated mechanism, whereby the bed roll is moved alternately to work receiving position and work presenting position and maintained in one position or the other until subsequent operation of the treadle operated clutch mechanism.
